UNITED STATES PATENT OFFICE.

JOSEPH H. MALHOIT, OF WEST HAVEN, AND ALFRED O. POIRIER, OF NEW HAVEN,
CONNECTICUT.

TIMING DEVICE FOR EXPLOSIVE-ENGINES.

1,297,212.

Specification of Letters Patent. Patented Mar. 11, 1919.

Application filed July 26, 1917. Serial No. 182,852.

To all whom it may concern:

Be it known that we, JOSEPH H. MALHOIT and ALFRED O. POIRIER, citizens of the United States, residing, respectively, at West Haven and at New Haven, in the county of New Haven and State of Connecticut, have invented a new and useful Improvement in Timing Devices for Explosive-Engines; and we do hereby declare the following, when taken in connection with the accompanying drawings and the characters of reference marked thereon, to be a full, clear, and exact description of the same, and which said drawings constitute part of this application, and represent, in—

Fig. 1 a face view, partly in section, of a timing device for explosive engines constructed in accordance with my invention.

Fig. 2 a top or plan view of the same.

Fig. 3 a sectional view on the line 3—3 of Fig. 1.

Fig. 4 a perspective view of the timing ring with its ring-insulating material in contact shoes.

This invention relates to an improvement in timing devices for explosive engines. In the more general construction of timing devices for explosive engines, the casing to which the wires are attached is moved to advance or retard the spark, and this constant moving tends to break the wires. Furthermore, in case of necessity, it is difficult to repair.

The object of this invention is to provide a casing which will be fixed with relation to the engine and provide a movable ring which may be turned in the casing, and so that the wires are not disturbed in adjusting the timer, and the terminals for the wire are carried to a convenient point; and the invention consists in the construction herein-after described and particularly recited in the claims.

In carrying out our invention we employ a casing 4 adapted to be rigidly secured to an explosive gas engine in the usual way. Opening from the top of the casing is an upwardly extending tubular arm 5 supporting at its upper ends four terminals 6 for wires 7 which lead downward through the tube into the forward end of the casing which contains a block 8 of insulating material in which is located a series of hori-

zontally arranged sockets 9 with which the wires 7 are respectively connected. In each socket is a plunger 10 forced outward by a spring 11. These plungers are arranged in the path of the inner edges of four shoes 12 which are mounted in an insulating ring 13, which in turn is fixed in a timing ring 14 located entirely within the casing and which is provided with an upwardly extending lever 15 projecting outward through a slot 16 in the top of the casing. The lower end 17 of the lever is reduced in size to permit the lever to pass outward through a clearance slot 18 intersecting one end of the slot 16, and so that the timer ring may be removed from the casing when desired. The lever 15 is adapted to be operated from any convenient point, usually at the steering wheel. The usual timing roller 19 moved by the usual timing cam shaft travels around the inner face of an insulating ring 13, and as it passes from one shoe to another it makes and breaks a circuit to give a spark. If the ring is moved in one direction or the other, it will advance or retard the time of sparking. Should it be necessary, the timing ring may be readily removed from the casing, and a new ring inserted without necessitating the adjustment of any of the wires of the timing device, and the wires are so protected that the danger of their becoming saturated with oil so as to short circuit, is avoided.

We claim:

1. A timing device of the class described comprising a casing formed with a slot, a tubular arm opening into the casing and projecting upward therefrom, a block of insulating material mounted in the said casing, a series of horizontally arranged contact sockets located in the said block, contacts in said sockets, a timing ring entirely within and movable in said casing and formed with a lever projecting outward through the slot in the casing, a ring of insulating material fixed to the said timing ring, shoes mounted in the insulating material carried by the ring the inner edges of the shoes arranged in the path of the said contacts in the casing.

2. A timing device of the class described comprising a casing, a block of insulating material mounted in the said casing, contacts mounted horizontally in said block, a timing

ring mounted entirely within the said casting, a ring of insulating material fixed to said timing ring, shoes mounted on the inside of the insulating ring in the timing ring, and adapted to have their edges engage with said contacts in the block, and means for moving said timing ring.

In testimony whereof, we have signed

this specification in the presence of two subscribing witnesses.

JOSEPH H. MALHOIT.
ALFRED O. POIRIER.
